UNITED STATES PATENT OFFICE.

JAMES C. ANDERSON, OF HIGHLAND PARK, ILLINOIS.

BRICK-MACHINE.

SPECIFICATION forming part of Letters Patent No. 276,991; dated May 8, 1883.

Application filed March 30, 1883. (No model.)

To all whom it may concern:

Be it known that I, JAMES C. ANDERSON, a citizen of the United States, and a resident of Highland Park, in the county of Lake and State of Illinois, have invented certain new and useful Improvements in Machines for Making Bricks, of which the following, when taken in connection with the accompanying drawings, forming a part thereof, forms a full, clear, and exact description.

Referring to the drawings, Figure 1 is a side elevation of my improved machine as mounted on a dredging scow or boat. Fig. 2 is an end view of the same. Fig. 3 is a plan view. Fig. 4 is a sectional view of the pug or mixing mill and mold. Fig. 5 is a sectional view of a portion of the mold-sections. Fig. 6 is a view in perspective of a portion of the mold-chain.

My present invention relates to the manufacture of bricks, tiles, and like articles in a cheap and rapid manner, and at the same time utilizing the unctuous fatty clay formed in dredging river-channels for the production of brick, when combined with loamy or sandy clay, as will be more fully set forth; and to this end my invention consists in mounting on a scow-boat or vehicle two separate and distinct series of dredging and elevating buckets for dredging and elevating to a common receptacle or mixing-mill two different kinds of clay, which are therethroughly mixed and tempered and shaped into the desired form.

My invention consists, further, in molds or a series or endless chain of molds of peculiar construction, adapted to pass beneath the pug or mixing mill and receive their charge of clay therefrom, as will more fully hereinafter appear.

My invention consists, further, in certain details of construction and operation of parts, which will be fully described, and pointed out in the claims.

In many locations, especially in and about Chicago, Illinois, an underlying vein of unctuous fatty clay of considerable depth is found overlaid with a seam or vein of loam or sandy clay, so that in making common brick by the old process the main vein or unctuous clay is found to be too fatty to work alone, and the practice is to mix the fatty clay with sandy or loamy clay to give the proper consistence for

working. This unctuous or fatty clay alone produces just as good brick as when mixed with the loamy, sandy clay; but the difficulty in working it, owing to its sticky nature, renders it necessary to mix the loamy, sandy clay therewith to produce the best results. The loamy, sandy clay, however, does not make good brick when worked alone, for the reason that it lacks in cementing qualities, and will not hold together with that tenacity requisite in the formation of a good brick. In dredging to deepen the channels of rivers, this stratum or vein of unctuous or fatty clay is met with and is brought up by the dredging-buckets in a wet, soggy condition; but in digging to widen the rivers, and in the building of dikes, the loamy and sandy deposits are met with. My present plan is to dredge the unctuous clay from the beds of rivers and convey it to a mixing-chamber, while at the same time the loamy clay is being dug and carried to the same chamber, where the two clays are intimately mixed, thus producing a mass or body of clay which can be readily worked without adherence to the molds or inconvenience in handling. The dry, absorbing quality of the loamy clay readily takes up the surplus moisture from the unctuous clay, thus producing an even-tempered good working clay.

I will now proceed to describe the mechanism and appliances which I have found to be best adapted for the purpose of working the two kinds of clay, although the pugging or mixing machinery, together with the molding devices, can be used to advantage in making brick or tile from other kinds of clay or other plastic material.

Referring to the drawings, A designates a vessel, vehicle, or frame-work of any kind, on which or in which is mounted the main driving-shaft B, said shaft being mounted in suitable bearings, and provided with a driving or band pulley, C, which is connected by means of a driving-belt or other suitable appliances to any convenient source of power, preferably a steam-engine (not shown) properly mounted in the vessel. This engine may be so connected with the requisite mechanism as not only to drive the brick-making and dredging mechanism, but also to propel the vessel from one point to another. The shaft B is pro-

vided with a clutch-operating mechanism, D, by means of which the pulley C may be transformed or changed from a fast to a loose pulley. The shaft B is provided with a pinion-wheel, A', which meshes with and imparts motion to a pinion-wheel, B', on the shaft C', said shaft being also provided with a series of pulleys, which will be more fully hereinafter described.

D' is a shaft mounted in suitable bearings. It lies parallel with the shaft C' and derives motion therefrom by means of the pulleys *a a* and belt *a'*. To the outer end of the shaft D' is secured a bevel-gear wheel, *b*, which meshes with and imparts motion to the bevel-wheel *b'*, secured to the upper end of the pug-mill shaft E, a detailed description of which will be more fully hereinafter set forth. The outer end of the shaft C' is provided with a drum, C'', which supports and drives an endless chain of dredging and elevating buckets, E', said buckets being supported by a frame, F, the lower end of which is adapted to be raised and lowered by means of a chain and windlass. The frame F is braced or trussed to make the same rigid and strong, and also with friction-rollers *c* to support the buckets in their upward passage.

The dredging and elevating mechanism first described is designed to excavate and convey to the pug or mixing mill the unctuous clay found in the lower stratum, and owing to the variable depth of said stratum the frame F and chain of excavating-buckets are made sufficiently long to meet the exigencies of the case. The excavating-buckets E' discharge their load of clay into the mixing or pug mill through the spout F'.

I will now proceed to describe the mechanism for excavating and carrying the clay from the upper or loamy stratum of clay to the pug or mixing mill to be mixed with the unctuous clay taken from the lower vein, which, as before stated, is necessary in order to more readily work the unctuous or fatty clay.

The excavating-scoops and frame for carrying the same are similar in construction to the devices just described except in this: they are mounted on a swinging crane, so they can be moved around to excavate the clay within prescribed limits from one or both sides of the boat.

G is the swinging crane, properly secured in bearings, the trunnions of which are hollow to admit of a vertical shaft, G', passing therethrough, said shaft being provided with a worm-gear, I''', near the top, which meshes with a corresponding wheel, I'', on the drum-shaft H, which supports the frame H', and imparts motion to the series of excavating-buckets I. The lower end of the central shaft is provided with a bevel-gear wheel, *c'*, which meshes with a similar wheel, *d*, on the shaft d', said shaft receiving motion from the shaft C' by means of a belt, *e*, which passes over a cone-pulley, *e'*, on the shaft C', and a similar

cone-pulley, *e''*, on the shaft d'. The object of having the cone-pulleys for driving the elevating-buckets I is that by changing the belt—a principle well known in mechanics—the buckets can be made to travel fast or slow, and thus regulate the quantity of loamy clay to be delivered into the pug-mill, which is to be mixed with the unctuous clay. The vertical shaft G', which passes through the post of the swinging crane has its bearings separate from the bearings of the post, so that the gear-wheels which impart motion to said shaft and the gear-wheels which are driven by it will at all times occupy the same relative position toward each other and toward the excavating mechanism driven by it. This is an important consideration, for it enables the operator to swing the crane from one point to another to bring the excavating-buckets in contact with the clay-beds. The arm I' of the swinging crane is provided with sheaves or pulleys *f*, over which a rope passes from the winding-drum K', mounted on the post G, to a bail, f', secured to the lower end of the frame H', which bail, together with the excavating-buckets, is raised and lowered so as to bring the buckets in contact with or away from the vein of loamy or other clay. The rope-drum K' is provided with a pinion-wheel, *g*, which is driven by a worm-gear on the shaft g', said shaft being operated by a crank, *h*, and the drum K' may be provided with a locking or pawl-and-ratchet device, which will hold the same together with the excavating devices in any desired position.

I have just described the devices by which the two different kinds of clay are excavated and elevated to the mixing or pug mill at one and the same time, and the devices which regulate the supply of any one kind of clay to the mixing-mill. I will now proceed to describe the mixing or pug mill, together with the molding and brick-forming devices.

L is a cylinder or mixing-drum of the pug-mill, in which is suspended the pugging or mixing shaft L', said shaft being properly supported in bearings in the timbers or beams h' and driven by means of the bevel-wheel connection between said shaft and the shaft D'. The lower portion of the cylinder L is open, so as to admit of the free passage of the tempered clay into the molds. The cylinder L is also provided with an extended base, M, with the opening M', in or through which the endless chain of molds passes when being filled with clay, the side walls of the opening M' serving also as side walls for the molds.

i are cross-bars, secured in the bottom of the cylinder, which, in connection with the shoulder or bar *i*, serve to strike off the surplus clay and form the upper side of the brick.

The shaft L'' of the pug or mixing mill is provided with a series of screw-shaped disks, N, firmly secured thereto. These disks N are set wider apart at the top than at the bottom of the shaft, so that the clay fed in at the top

of the mill is forced down by the screw-disks into the molds below, and in its passage through the mill is sliced up finely and intimately mixed into a homogeneous mass.

5 N' is the chain of molds, composed of a series of steel castings, k, linked together, said castings being provided with a projecting flange, k', at one end, which, in connection with the flange k' of the adjacent section, form the boundary 10 or division of the mold-sections. The castings k are provided with grooves l, and the flanges k' are divided into sections, leaving an open space, l', between them, so that the knives which sever the clay into sections can pass therethrough.

15 O is a knife or a series of knives, secured in the throat of the cavity of M', the lower ends of which project downward and forward into the grooves l of the mold-sections, so as to sever 20 the clay which has been forced into the mold-sections into the desirable size.

I have shown the endless chain of molds as constructed to make four bricks at one time; but it is obvious that the mold-sections can be 25 made so as to make any desired number.

It will be noticed that the sides of the opening M' form the sides of the mold-sections while the same is passing therethrough, and that the clay is forced down into the mold-sections by the action of the pugging-screw, the surplus of clay being struck off or forced back into the adjacent mold-sections by the scrapers or bars i and i', while the knives O sever the clay in a longitudinal direction, as before stated. The endless chain of mold-sections pass over the drums O' and P, the drum O' being provided at one end with a miter-wheel, which engages with a similar wheel on the shaft m, said shaft being driven by a band, n', 30 which passes over a pulley, n, on the shaft m, and over a pulley, n, secured to the shaft D'; and it is by the means just described that the mold-chain or chain of endless molds are caused to travel through the lower portion of 35 the pug or mixing mill to receive their charge of clay and convey the same away in the shape of a finished brick or tile. The frame P', which supports the drums O' and P, is also provided with a series of friction-rollers, o, which support the endless chain of molds after they are 40 filled with clay. The frame P' and endless chain of molds may be of any convenient or desired length, so as to convey the brick to the shore or to any desired point on the scow 45 or boat, when they are stacked up to dry.

In order to prevent the more unctuous or fatty clays from sticking to the molds, the mold-sections are made to pass through a tank of water, Q, which moistens or lubricates the 50 molds, and removes therefrom any clay which may have adhered thereto. The mold-sections pass from the tank Q beneath the sanding-box Q', from which a spray of sand gravitates upon the molds, so that when the wetting or sanding 55 of the molds is necessary it can be done automatically.

In some of the fatty clays the operation of sanding the molds will be found unnecessary, as the wetting alone will be sufficient to cause the bricks to drop from the mold after they 60 have passed or while they are passing over the drum P.

I prefer to make my dredging and elevator buckets of cast-steel, cast in one piece, so that there will be no rough edges or projections to 65 catch and retain the clay; and, furthermore, buckets cast from steel are better able to withstand the wear and tear of the dredging operation. I do not, however, in this application desire to claim a dredging, excavating, or 70 elevator bucket cast in one piece from steel; but reserve the right to make a separate application for a patent for the same.

It will be noticed that by the method and means described bricks and tiles can be made 75 rapidly and cheaply; that the clay is taken direct from the bed or pit and conveyed to the mixing and molding mechanism by the devices and combination of devices described, so that the handling of the clay by manual labor is 80 obviated; also, that by means of the cone-pulleys the amount of clay from the loamy vein can be so regulated that the supply will always be of the proper proportion to mix with the unctuous fatty clay to form a good marketable 85 brick.

Having thus described my invention, what I claim, and desire to secure by Letters Patent, is—

1. The method herein described of making 90 brick, the same consisting in dredging or excavating two or more clays at the same time and in predetermining proportional quantities, conveying the same to a mixing and tempering mill and thoroughly mixing the same, and then forming the same into bricks or tiles in 95 one continuous operation, as set forth.

2. A plant for the manufacture of brick, tiles, &c., mounted on a boat or suitable movable or stationary frame-work, and consisting 100 of two sets of clay dredging and elevating buckets adapted to discharge different kinds of clay into a mixing-mill, a mixing or pugging mill provided with a suitable mixing-shaft, and a series of mold-sections adapted to traverse 105 beneath and receive their charge of clay from the mixing-mill, and devices, substantially such as described, for finishing the top of the brick and cutting the clay into bricks, as set forth.

3. In a machine for making brick, tile, &c., a series of elevating-buckets, the supporting-frame of which is pivoted at its upper end to a fixed axis, and a supplemental series of elevating-buckets mounted on a swinging crane and adapted to be moved from side to side or from one point to another without changing the relation of the buckets to the driving mechanism, as set forth.

4. A crane for supporting a series of dredging and excavating buckets, provided with hollow trunnions through which or in which

the bucket-operating mechanism is located, as set forth.

5. A series or chain of dredging or excavating buckets supported by a swinging crane, and devices, substantially such as described, for continuously moving or operating the buckets, as set forth.

6. An endless chain of brick-forming molds, consisting of sections of cast-steel pivoted together, as shown, the sections being provided with upwardly-projecting flanges which constitute the ends or sides of the mold, said projections being recessed or divided to allow of the passage of the cutting-knife therethrough, as set forth.

7. An endless chain of brick-forming molds composed of the sections *k*, provided with the recessed or divided flanges *k'*, and the grooves or recesses *l*.

8. An endless chain of brick-forming molds composed of the sections *k*, provided with the flanges *k'*, and grooves or recesses *l*, in combination with a knife or series of knives, *O*, which project into said grooves *l*, as set forth.

9. In a brick-machine, an endless chain of brick-forming molds adapted to traverse a cavity in the lower portion or beneath the mixing-mill, the walls of said cavity arranged to form the outer walls of the mold, in combination with devices for leveling the clay within the mold-sections, and a series of knives which sever the clay in a longitudinal direction, as set forth.

10. The combination of the endless chain of brick-forming molds with the tank or reservoir of water *Q*, the molds being arranged to dip into the water to wash off any clay which may have adhered to the molds and to lubricate the same, as set forth.

11. In a brick or tile machine, an endless chain of brick-forming molds or compartments, in combination with water-tank for wetting or washing the molds, and a sanding box or hopper for spraying or distributing sand in the molds, all arranged to operate substantially in the manner described.

12. In a clay-mixing or pugging machine, the mixing-shaft *L'*, provided with a series of spiral cutting and mixing disks, *N*, the disks on one end of the shaft being arranged in closer proximity to each other than the disks on the opposite end, as set forth.

13. In a brick-machine of the character described, the pug or mixing mill provided with a mixing-shaft suspended therein, and a hollow extension, *M*, in combination with the scrapers or cross-bars *i i*, whereby the clay is forced compactly into the molds and the surplus of clay removed therefrom.

14. The shaft *B*, pinion-wheels *A'* and *B'*, shafts *C* and *D* with their pulley-wheels and connecting-belt, in combination with the elevator-buckets *E'* and mixing-shaft of the pug-mill, as set forth.

15. The shaft *B*, pinion-wheels *A'* and *B'*, shafts *C* and *D* with their pulley-wheels and connecting-belt, with the shaft *d'* and vertical shaft within the trunnions of the crane, whereby motion is imparted to the two series of excavating and elevating buckets and the pug-shaft, as set forth.

16. The shaft *C'*, provided with a cone-pulley, *e'*, and shaft *d'*, provided with a pulley and a connecting-belt, *e*, in combination with a vertical shaft located within the post of the crane and the shaft for driving the elevator-buckets *I*, as set forth.

17. The combination of the cone-pulley *e'* with the belt *e*, shaft *d'*, and the mechanism connected therewith for driving the elevator-buckets *I*, whereby the speed of travel of said buckets is regulated to increase or diminish the amount of loamy or other clay which is to be mixed with the clay delivered by the other series of buckets, as set forth.

J. C. ANDERSON.
